UNITED STATES PATENT OFFICE.

JOHN LINCOLN TATE, OF CHESTER, PENNSYLVANIA.

STEAM ENGINE.

1,406,700.

Specification of Letters Patent. Patented Feb. 14, 1922.

Application filed March 28, 1918. Serial No. 225,322.

To all whom it may concern:

Be it known that I, JOHN LINCOLN TATE, a citizen of the United States, residing at Chester, in the county of Delaware and 5 State of Pennsylvania, have invented certain new and useful Improvements in Steam Engines, of which the following is a specification, reference being had therein to the accompanying drawing.

10 This invention relates to improvements in steam engines and more particularly to an improved system or means for super-heating steam or treating the same to increase the expansive force or power thereof for use in

15 such engines.

The object of the invention is to provide an improved system or means of the character referred to that will be more economical than the methods in use, and that will in 20crease the general efficiency and power of the engine.

The invention, with other objects and advantages thereof and the particular construction, combination and arrangement of 25 parts comprising the same will be understood from the following detail description when considered in connection with the accompanying drawings, forming part hereof and illustrating one embodiment of the in 30vention.

In the drawings:

Figure 1 is a horizontal longitudinal section of a portion of a steam engine equipped with improved means for super-heating or 35 treating steam in accordance with the invention.

Figure 2 is a longitudinal section, on an enlarged scale illustrating adjoining portions of the cylinders and the valve controlling the passage between the same;

Figure 3 is a transverse section on the line 3—3 of Figure 1.

Fig. 4 is a detail view showing the controlling valve in end elevation.

Fig. 5 is a side elevation with parts shown in section of the structure illustrated in Fig. 1, and also showing in a general way the valve for the steam cylinder, and the steam generator.

50 The invention comprehends an improved system or means for treating the steam directly in the cylinder of the engine on the power stroke, the application of heat thereto to raise the pressure and also augmenting 55 the power of the charge by adding pressure thereto. The invention comprehends an im-

proved system of this nature that will operate automatically when the pressure of the steam supplied to the cylinder of the steam engine is less than a predetermined amount. The invention contemplates for this purpose the use of an auxiliary cylinder and piston, the auxiliary cylinder having an intake controlled by a check valve and connected with a suitable supply of gas or explosive mixture such as a carburetor or the like. The auxiliary piston and cylinder operate in a manner similar to an internal combustion or explosive motor to draw in a charge of combustible mixture and to compress the same. The piston of the auxiliary gas cylinder is connected with the piston of the steam engine to operate in timed relation therewith, so that a compression stroke of the piston of the gas engine is timed with the power stroke of the piston of the steam engine. A passage is provided between the steam engine cylinder and the auxiliary gas cylinder, said passage being controlled by a valve which keeps the passage between the two cylinders closed as long as the pressure in the auxiliary gas cylinder does not exceed the pressure of the steam in the steam engine cylinder on the power stroke thereof, but which opens automatically and establishes communication between the cylinders whenever the pressure in the auxiliary gas cylinder exceeds the pressure in the steam engine cylinder. Means is provided for igniting the compressed charge of combustible mixture in the auxiliary gas cylinder upon the opening of the valve that controls the passage way between the cylinders, the heat and pressure of the explosive charge being emptied or discharged into the steam engine cylinder. In accordance with my improved system, the heat of the cooling water from gas engine cylinder is utilized in the steam boiler.

100 In the drawings, I have illustrated, by way of example, a specific embodiment of the invention, but I desire it to be understood that changes and variations in the particular construction shown, and the carrying out of the invention in other forms, as will appeal to those skilled in the art, and falling within the scope of the appended claims 105 may be made without departing from the spirit of the invention.

110 Referring to a detail description of the drawings, wherein like reference characters designate corresponding parts throughout

the several views, 1 and 2 designate respectively the cylinder and piston of a steam engine. 3 is the steam inlet port of the cylinder controlled by the usual slide valve and gear. In the drawings, by way of example, one of the conventional forms of slide valve structures is illustrated in a general way, the valve gear not being shown. 3' is the valve adapted to slide on the seat 3^b within the chest 3^c. a designates an induction port and b the exhaust. 3^a is the steam boiler or generator, and 3^d is the supply pipe leading from the boiler 3^a to the chest 3^c.

4 designates the auxiliary gas engine cylinder, which in the present instance is shown located at one end and in longitudinal alignment with the steam engine cylinder, the piston 5 of the auxiliary gas engine cylinder being connected with the steam engine cylinder to reciprocate in unison therewith, with the compression stroke of the gas engine piston 5 timed to take place with the power stroke of the steam engine piston. The auxiliary gas engine cylinder 4 is secured to the head 1' of the steam engine cylinder by bolts 6, suitable packing 7 being provided to make a fluid tight joint between the parts. The steam engine piston 1 and the gas engine piston 5 are connected to operate together by longitudinally extending rods 8 slidably supported in guides 9 on the cylinder 1, and short transversely extending rods 10—11 rigidly connecting opposite ends of the rods 8 with the steam engine piston rod 12 and the piston rod 13 of the gas engine piston 5. The auxiliary gas engine cylinder at one end adjacent the steam engine cylinder has a gas intake 14 controlled by a check valve 15 of any suitable construction. 16 designates a carbureter of any approved construction connected with the intake 14 of the gas engine cylinder 4 by a conduit 17. The gas engine cylinder at its other end is provided with air intake pipes 18 and an annular chamber 19 formed in the cylinder wall having annular outlet ports 20—21 at opposite ends leading to the interior of the cylinder, air intake pipes 18 leading to said annular chamber and being provided with suitable check valves 22 and graduating valves 23.

The cylinder head 1^a is provided with an opening 24 forming a communicating passage between the cylinders 1 and 4, and 25 is a valve controlling the said passage. As shown the walls of the opening 24 are tapered to provide a seat for the valve. The valve 25 is carried by a plate 26 slidably supported on pins 27 extending from the cylinder head 1. The pins 27 at their outer ends have heads 27' and arranged on said pin between the heads thereof and the plate 26 are coiled springs 28, which act to force the valve 25 to its seat, the valve and its associated parts being located within a recess 29 at the inner side of the cylinder head 1'.

Any suitable ignition or sparking mechanism may be employed. The construction illustrated in the drawing, which I consider of special advantage, is of the break spark type and consists of a contact member 30 mounted on the cylinder adjacent the opening 24, and a cooperating contact member 31 carried by the valve 25, the contact members being suitably connected with a sparking circuit. A conductor 32 is shown leading to the contact member 30. The electrical connection with the other movable contact member 25 may be made by grounding the other terminal of the circuit in accordance with the usual practice.

The operation of the system is as follows:

Steam is fed from the steam boiler 3^a to the steam engine cylinder 1 in the usual way, the steam entering the inlet port 3 of the cylinder, the feeding of the steam being controlled by the usual sliding valve. If the pressure in the steam boiler is say 150 lbs. per square inch, it is likely that the pressure in the steam engine cylinder, where the steam is entering will not be more than 100 lbs. on account of wire drawings, etc. As the steam enters, it is cut off at the inlet port 3 and expands from thereon losing temperature. As the steam engine piston moves forwardly, the gas engine piston 5 follows in the auxiliary gas cylinder compressing the mixture of gas and air that was drawn in on its out stroke. On the inward stroke of the gas engine piston air is drawn into the auxiliary gas engine cylinder 4 through the air intake 18 and upon the return stroke of the piston 5 the air is compressed and transferred around the piston, the annular chamber 19 with its spaced outlet ports 20 and 21 serving as a bypass, the pressure being thus increased above atmospheric in the auxiliary gas engine cylinder before the compression stroke begins. As will be understood, the drawing-in of the combustible mixture, and the compressed air transfer is practically simultaneous, the compressed air transfer taking place near the end of the outstroke of the piston into the unsatisfied vacuum resulting from the suction on the carbureter. This pressure is regulated by the graduating cocks 23, the check valves 22 preventing escape of the air drawn into the cylinder but allowing sufficient air to enter and regulate the compression in the gas cylinder as desired. When the pressure in the gas engine cylinder exceeds the steam pressure in the steam engine cylinder, the valve 25 opens and upon the opening of the valve the contact member 31 of the sparking mechanism is moved out of engagement with the contact member 30 so that a spark is made and the combustible gas and air mixture in the gas engine cylinder is ignited. This increases the pressure and temperature in the gas engine cylinder several times

- and, because of this increased pressure, the exploded charge empties itself or discharges into the steam engine cylinder behind the piston therein, the temperature and pressure therein being increased in proportion as the area therein is to the area of the steam engine piston, and the temperature as to the temperature in the steam engine cylinder behind the steam engine piston.
- 5 10 As will be understood the valve 25 is held to its seat to close the passageway between the cylinders always while steam is being admitted to or exhausted from the steam engine cylinder, and opens automatically 15 only when the pressure in the gas engine cylinder exceeds the pressure of the steam in the steam engine cylinder.
- The gas engine piston 5 is arranged to travel clear to the end of the cylinder so that 20 all burned gases are expelled directly after each explosion, the gas engine being adapted to operate so that an explosion occurs on each complete revolution of the crank shaft.
- A water cooling system of any suitable 25 form is provided for the auxiliary gas engine cylinder, the cylinder and seat for the valve 25 being shown provided with jackets 34, 34' for the circulation of the cooling water, and a force pump (not shown) working in stroke with the steam engine is preferably employed in order to insure a sufficient supply of the cooling water. The heat of the water from the cooling system is utilized in the steam engine boiler 3^a, a conduit 35 leading from the water jacket to the steam boiler 3^a. 35' designates the cooling water supply pipe.
- It will be noted that my improved system 30 of superheating and treating the steam directly in the cylinder of the engine, possesses advantages of considerable practical importance. The heat is not dissipated in pipes en route to the cylinder as in the methods commonly employed. There is also 35 less heat loss as the mixture of steam and carbon dioxide does not condense on cooling surfaces as readily as steam alone. It will also be noted that the maximum pressure is not applied to the steam engine piston on 40 dead center, but does occur when the crank pin is in the most advantageous position to transmit it. Further, more effective use is made of the pressure derived from the explosion in the gas engine than in the conventional explosive motors in which the exhaust valve is opened when there is still 45 about 40 lbs. pressure in the cylinder. As the steam in the cylinder is released at a pressure very much less than 40 lbs., it is 50 apparent that greater efficiency is secured from the gas engine. Increased efficiency also results because the burned contents are completely expelled after each explosion.
- 55 What I claim is:
- 60 1. The combination with a steam engine including a cylinder and piston, of means for furnishing a medium for adding heat to the steam in the cylinder of the engine, a connection between said means and the cylinder of the engine, and a valve controlling 70 said connection opening automatically to permit said medium to enter the cylinder when the pressure of the charge of steam in the cylinder falls below a predetermined degree.
2. The combination with a steam engine 75 including a cylinder and piston, of means for furnishing a medium for adding pressure to the steam in the cylinder of the engine, a connection between said means and the cylinder of the engine, and a valve controlling said connection opening automatically to permit said medium to enter the cylinder when the pressure of the charge of steam in the cylinder falls below a predetermined degree.
- 80 3. The combination with a steam engine including a cylinder and piston, a combustible gas supply, a connection between said combustible gas supply and the cylinder of the steam engine, a valve controlling said connection opening automatically when the pressure of the steam in the engine cylinder falls below a predetermined degree, and ignition means for the combustion charge.
- 85 4. The combination with a steam engine 90 including a cylinder and piston, of means acting automatically to heat the steam in the cylinder when the pressure of the same falls below a predetermined degree, said means including an auxiliary cylinder and 95 piston, means for supplying combustible gas to the auxiliary cylinder, a connection between the auxiliary cylinder and the steam engine cylinder, and a valve controlling said passage and acting automatically to open 100 when the pressure of the steam in the cylinder falls below a predetermined degree.
5. The combination with a steam engine 105 including steam generating means, and means for feeding the steam to the engine, 110 of means independent of the first mentioned steam generating means and acting automatically to introduce into the steam engine cylinder during the power stroke a medium for raising the pressure of the charge of steam 115 in the cylinder when the pressure of the steam falls below a predetermined degree.
6. The combination with a steam engine 120 including a cylinder and piston, of means acting automatically to heat the steam in the cylinder, said means including an auxiliary cylinder and piston, means for supplying combustible gas to the auxiliary cylinder, a connection between the auxiliary cylinder and the steam engine cylinder, and a valve 125 for said passage operated automatically by the difference of pressures in the steam engine cylinder and the auxiliary cylinder.
7. The combination with a steam engine 130 including a cylinder and piston, of means

- for adding heat to the steam in the cylinder, said means including an auxiliary cylinder and piston, means for supplying combustible mixture to the auxiliary cylinder, said steam engine cylinder and the auxiliary cylinder being arranged end to end, a connection between the adjacent ends of the steam engine cylinder and the auxiliary cylinder, and a valve controlling said connection.
- 10 8. The combination with a steam engine including a cylinder and piston, of an auxiliary cylinder and piston, a combustible mixture supply connected with the auxiliary cylinder, the piston of the auxiliary cylinder being adapted to draw combustible mixture into the auxiliary cylinder and compress the same, a passage between the steam engine cylinder and the auxiliary cylinder, a valve for said passage controlled by the difference of pressure in the steam engine cylinder and the auxiliary cylinder, and sparking mechanism operating to generate a spark upon the opening of said valve.
9. The combination with a steam engine including a cylinder and piston, of an auxiliary cylinder and piston, a combustible mixture supply connected with the auxiliary cylinder, the piston of the auxiliary cylinder being operatively connected with the steam engine piston and adapted to draw combustible mixture into the auxiliary cylinder and compress the same, a passage between the steam engine cylinder and the auxiliary cylinder, a valve for said passage controlled by the difference of pressures in the steam engine cylinder and the auxiliary cylinder, and sparking mechanism operating to generate a spark upon the opening of said valve.
- 10 10. The combination with a steam engine including a cylinder and piston, of an auxiliary cylinder and piston, a carburetor connected with the auxiliary cylinder, the piston of the auxiliary cylinder being adapted to draw combustible mixture into the auxiliary cylinder and compress the same, a passage between the steam engine cylinder and the auxiliary cylinder, a valve for said passage controlled by the difference of pressure in the steam engine cylinder and the auxiliary cylinder, and sparking mechanism to ignite a charge of combustible mixture compressed in the auxiliary cylinder.
11. The combination with a steam engine including a cylinder and piston, of an auxiliary cylinder and piston, a combustible mixture supply connected with the auxiliary cylinder, a valve controlled passage between the steam engine cylinder and the auxiliary cylinder, the piston of the auxiliary cylinder being operatively connected with the steam engine piston to operate in timed relation therewith, with a compression stroke of the piston of the auxiliary cylinder timed with the power stroke of the steam engine, and
- means for igniting a charge of combustible mixture compressed in the auxiliary cylinder.
12. The combination with a steam engine including a cylinder and piston, of an auxiliary cylinder and piston, a combustible mixture supply connected with the auxiliary cylinder, a valve controlled passage between the steam engine cylinder and the auxiliary cylinder, the piston of the auxiliary cylinder being operatively connected with the steam engine piston to reciprocate in unison therewith with the compression of the piston of the auxiliary cylinder timed with the power stroke of the steam engine piston, and means for igniting a charge of combustible mixture compressed in the auxiliary cylinder.
13. The combination with a steam engine including a cylinder and piston, of an auxiliary cylinder and piston arranged at one end of and in longitudinal alignment with the steam engine cylinder and piston, a combustible mixture supply connected with the auxiliary cylinder, a valve controlled passage between the steam engine cylinder and the auxiliary cylinder, the piston of the auxiliary cylinder being operatively connected with the steam engine piston to reciprocate in unison therewith with the compression stroke of the piston of the auxiliary cylinder timed with the power stroke of the steam engine, and means for igniting a charge of combustible mixture compressed in the auxiliary cylinder.
14. The combination with a steam engine including a cylinder and piston, of an auxiliary cylinder and piston, a combustible mixture supply connected with the auxiliary cylinder, a passage between the steam engine cylinder and the auxiliary cylinder, a valve controlling said passage controlled by the difference of pressures in the steam engine cylinder and the auxiliary cylinder and adapted to open when the pressure in the auxiliary cylinder exceeds that of the pressure in the steam engine cylinder, the piston of the auxiliary cylinder being operatively connected with the steam engine piston to reciprocate in unison therewith with the compression stroke of the piston of the auxiliary cylinder timed with the power stroke of the steam engine piston, and means acting automatically to generate a spark to ignite a charge of combustible mixture compressed in the auxiliary cylinder upon the opening of said valve.
15. The combination with a steam engine including a cylinder and piston, of an auxiliary cylinder and piston, a combustible mixture supply connected with the auxiliary cylinder, the piston of the auxiliary cylinder being adapted to draw combustible mixture into the auxiliary cylinder and compress the same, a passage between the steam engine cylinder and the auxiliary cylinder, a reciprocating valve for said passage con-

- trolled by the difference of pressure in the steam engine cylinder and the auxiliary cylinder and adapted to open when the pressure in the auxiliary cylinder exceeds that 5 of the pressure in the steam engine cylinder, springs acting to normally hold the valve to its seat, and sparking mechanism operating automatically to generate a spark upon the opening of the said valve.
- 10 16. The combination with a steam engine including a cylinder and piston, of an auxiliary cylinder and piston, said cylinder having a valve controlled intake near one end thereof, a carburetor connected with said 15 intake, and said cylinder having at its opposite end an air intake and a by-pass passage connected with the interior of the cylinder and the said air intake, the piston of the auxiliary cylinder being adapted to draw 20 gas and air into the auxiliary cylinder and compress the same, a passage between the steam engine cylinder and the auxiliary cylinder, a valve for said passage controlled by the difference of pressures in the steam 25 engine cylinder and the auxiliary cylinder, and means for igniting a charge of combustible mixture compressed in the auxiliary cylinder.
17. The combination with a steam engine 30 including a cylinder and piston, of an auxiliary cylinder and piston, a combustible mixture supply connected with the auxiliary cylinder, the piston of the auxiliary cylinder being adapted to draw combustible mixture 35 into the auxiliary cylinder and compress the same, a valve controlled passage between the steam engine cylinder and the auxiliary cylinder, and means for igniting a charge of combustible mixture compressed in the
- auxiliary cylinder, said auxiliary piston being adapted to travel clear to the end of the auxiliary cylinder. 40
18. The combination with a steam engine including a cylinder and piston, of an auxiliary cylinder and piston, a combustible 45 mixture supply connected with the auxiliary cylinder, the piston of the auxiliary cylinder being adapted to draw combustible mixture into the auxiliary cylinder and compress the same, a valve controlled passage between the 50 steam engine cylinder and the auxiliary cylinder, and means for igniting a charge of combustible mixture compressed in the auxiliary cylinder, said auxiliary piston being adapted to travel clear to the end of the 55 auxiliary cylinder, and the gas engine cylinder and piston being capable of operating so that an explosion occurs upon each revolution of the crank shaft. 60
19. The combination with a steam engine including a cylinder and piston, of means for adding heat to the steam in the cylinder, said means including an auxiliary cylinder and piston, a combustible gas supply connected with the auxiliary cylinder, a passage between the steam engine cylinder and the auxiliary cylinder, a valve for said passage controlled by the difference of pressures in the steam engine cylinder and the auxiliary cylinder, said auxiliary piston 65 operating in timed relation with the steam engine piston. 70

In testimony whereof I hereunto affix my signature in the presence of two witnesses.
